AUTOMATIC TRANSMISSION FILLER SPOUT

Frank H. Liljemark, Minneapolis, Minn., assignor to
Electro - Specialty Manufacturing Co., Minneapolis,
Minn., a corporation of Minnesota

Filed Aug. 16, 1962, Ser. No. 71,334

Term of patent 14 years

(Cl. D58—26)

FIG. 1 is a side elevational view of an automatic transmission filler spout, showing my new design;

FIG. 2 is a top plan view thereof;

FIG. 3 is an end elevational view thereof taken from the left of FIG. 1; and

FIG. 4 is a fragmentary side elevational view of the side opposite that shown in FIG. 2 and taken from the end of the cutting element to the beginning of the hose.

The side opposite that shown in FIG. 1 is a mirror image of the side shown.

A characteristic feature of the invention is that part thereof intermediate of the ornamental head carrying the cutter and the flexible hose with the spout at the extreme outer end thereof and which intermediate portion is comprised of a fitting, the opposite medial portions being similar and converging inwardly and merging into a semi-circular surface on opposite sides of that fitting, and there being an outwardly projecting valve member in

alignment with the oppositely disposed semi-cylindrical surfaces.

I claim:

The ornamental design for an automatic transmission filler spout, as shown and described.
